UNITED STATES PATENT OFFICE.

OLIVER C. RITZ WOLLER, OF CHICAGO, ILLINOIS.

DESIGN FOR AUTOMOBILE SIGNAL LAMP CASING.

Application filed May 6, 1926. Serial No. 17,585. Term of patent 7 years.

To all whom it may concern:

Be it known that I, OLIVER C. RITZ WOLLER, a citizen of the United States, residing at Chicago, in the county of Cook and State of Illinois, have invented a new, original, and ornamental Design for Automobile Signal Lamp Casings, of which the following is a specification, reference being had to the accompanying drawing, forming part thereof.

In the drawing—

Fig. 1 is a front elevational view and Fig. 2 is an end elevational view of an automobile signal lamp casing showing my new design.

I claim:

The ornamental design for an automobile signal lamp casing as shown.

OLIVER C. RITZ WOLLER.
